ELECTRICAL TIMING DEVICE

Peter J. Dugan, Crestwood, N. Y.

Application November 19, 1941, Serial No. 419,737

8 Claims. (Cl. 171—97)

My invention relates to an electrical timing device and more particularly to an electrically operated timing device for controlling an electrical circuit intermittently so that said circuit will be operative for a predetermined period and inoperative for a predetermined period.

The objects, features and advantages of my invention will appear from the following description and accompanying drawing, in which the single figure illustrates diagrammatically a circuit and apparatus that may be used in carrying out my invention.

Referring to the drawing in detail, there is a line switch 10 which when closed connects the timing device to a source of electrical energy thereby placing it in condition for operation. When the switch 10 is closed, a coil 11' of a control relay 11 connected to the line through conductors 30, 31, contacts 12 and conductors 32, is energized, causing the control relay 11 to operate to close contacts 13, 14 and 15. The control relay 11 is of such a type that when the coil 11' is not energized, the contacts 13, 14 and 15 will automatically open.

The closing of contacts 13 and 14 connects a motor 16 of a motor generator set and its series field coil 17 to the line through conductors 33, 34, 35 and 36. This places the motor 16 in operation, driving the generator 18 and a flywheel 19 mounted on a drive shaft connecting the motor 16 and the generator 18.

The closing of contacts 15 by the control relay 11 energizes a coil 20' of a differential relay 20. The coil 20' is connected to the line through conductors 36, 37, 38, 39 and 32 and contacts 15. The differential relay 20 is so arranged that the effect of the coil 20' is opposed by the effect of a second coil 20'' connected through conductors 40 and 41 to the output of the generator 18. When the motor 16 brings the generator 18 up to a certain predetermined speed, the generator 18 will supply sufficient energy to the coil 20'' so that the effect of the coil 20'' will overcome that of the opposing coil 20'. Due to the action of this coil 20'', the differential relay 20 will operate to open contacts 12 and to close contacts 21. The differential relay is of a type that when the coils are de-energized the contacts 12 and 21 will automatically return to their original conditions.

The opening of contacts 12 interrupts the circuit to the control relay 11, de-energizing the coil 11' of that relay and thereby permitting contacts 13, 14 and 15 to open. The closing of contacts 21 places the circuit being controlled in operation or, in other words, completes the circuit to the work.

During the time required to bring the generator 18 up to a speed sufficient to operate the differential relay 20, contacts 21 have been open and the working circuit inoperative. This time may be

regulated by varying an adjustable resistance 22 connected in series with the shunt field 23 of the generator 18 across its output in parallel with the coil 20'' of the differential relay. This arrangement permits this time to be easily regulated within very close limits.

After contacts 21 have been closed, they will remain closed as long as the generator 18 continues to supply current to the coil 20'' of the differential relay 20. This is due to the fact that the circuit to the first-mentioned coil 20' of the differential relay 20 is interrupted by the opening of the contacts 15, as described, and the opposing coil 20'' no longer has to overcome the effect of that coil.

After the motor 16 has been disconnected from the line by the opening of contacts 13 and 14, as described, so that the motor no longer drives the generator 18, the rotation of the generator 18 continues due to the flywheel 19 and current is supplied to the coil 20'' of the differential relay 20 until the generator comes to rest. The time during which the generator will continue to operate under such conditions depends on the characteristics of the flywheel 19 and the inertia forces stored therein.

When the generator 18 stops its rotation and ceases to supply current to the coil 20'' of the differential relay, the differential relay 20 is no longer energized and permits contacts 12 to close and contacts 21 to open. To neutralize any residual effect in the coil 20'' connected to the generator 18, the opposing coil 20' is connected to the line through a high resistance 24 which is selected so that it will permit only enough current to flow through it and the coil 20' to neutralize such effect, thus insuring operation of the differential relay 20 when the generator 18 comes to rest.

The opening of contacts 21 interrupts the working circuit and the closing of contacts 12 completes the circuit to the coil 11' of the control relay 11 so that the sequence of operations just described will be repeated.

In describing my invention I have, for purposes of illustration, shown one working circuit as being controlled through contacts 21 operated by the differential relay 20; however, this may be modified so that these contacts are operated by the control relay 11; or so that circuits are operated by both relays if desired. In other words, the timing device described herein may be utilized in various ways depending upon the conditions and requirements to be met and it is not intended to limit it to the particular use shown and described herein. One application of my device is shown in my copending application, Serial No. 394,493.

It will also be understood that while I have shown and described a preferred embodiment of my invention, various modifications may be made

by those skilled in the art without departing from the spirit or scope of my invention as described in the appended claims.

I claim:

PETER J. DUGAN.
